CLAIM

The ornamental design for a bottle, as shown and described.

DESCRIPTION

FIG. 1 is a perspective view of a bottle embodying our new design;

FIG. 2 is a top view of the bottle;

FIG. 3 is a bottom view of the bottle;

FIG. 4 is a front view of the bottle;

FIG. 5 is a side elevational view from the left side of the bottle as shown in FIG. 1;

FIG. 6 is a rear view of the bottle; and,

FIG. 7 is a side elevational view thereof from the right side.
